UNITED STATES PATENT OFFICE.

JOSEPH W. FISKE, OF NEW YORK, N. Y.

DESIGN FOR A PEDESTAL.

Specification forming part of Design No. 7,605, dated August 4, 1874; application filed July 14, 1874.
[Term of Patent 7 years.]

To all whom it may concern:

Be it known that I, JOSEPH W. FISKE, of New York, in the county of New York and State of New York, have invented certain Improvements in Pedestals for Vases, Statuary, &c., of which the following is a specification:

My design consists of a rectangular shaft or body, B, having an enlarged base, A, above which is a beveled molding, a, and above that a small oval molding, b. The angles of the shaft B are beveled, and on each face of the body is sunken panel b², at the upper corners of which are rosettes b³. Above the panel it is surrounded by a small oval molding, above which, on each of its four faces, is an incised ornamental scroll. Upon the top of the body B is a cap, C, the lower edges of which pro-

ject laterally, its upper portion decreasing gradually in diameter to the size of the body below, the projecting portion having on each of its four faces a break, terminating in a point, c, above, at the center, as shown in the illustration.

Thus I produce a very ornamental pedestal, adapted for the support of vases, statuary, or other ornamental figures in pleasure-grounds, lawns, cemeteries, and similar places.

What I claim is—

The design for a pedestal, substantially as shown and described.

JOSEPH W. FISKE.
